TEMPERATURE RESPONSIVE DEVICE

Filed Nov. 19, 1930

UNITED STATES PATENT OFFICE

EMIL TYDEN, OF HASTINGS, MICHIGAN

TEMPERATURE RESPONSIVE DEVICE

Application filed November 19, 1930. Serial No. 496,307.

The purpose of this invention is to provide an apparatus adapted to be easily installed in a building or apartment for operating by a temperature-responsive device any sort of a device or apparatus for protecting the building or any apartment thereof from fire.

The invention consists in the elements and features of construction shown and described as indicated in the claims.

In the drawing:

Figure 1 is a diagrammatic view showing in partly sectional elevation a thermostatic operating device embodying the invention in diagrammatically indicated association with two typical fire protective devices, which are selected as specimens to indicate a wide variety of protective expedients and devices which are included within the scope of this invention.

Figure 2 is a detail section in the same plane as Figure 1 for more clearly showing the detailed construction of the thermostatically operated parts.

The present invention is most definitely characterized by details of the valve device which controls the release of the fluid pressure, which, according to the purpose and principle of the invention, brings into operation the various fire protective devices of the total installation.

An absolutely essential requisite in respect to the means of control is that it shall be such as to reliably prevent leak of the control fluid pressure during the intervals between instances of release of that pressure for operating the protective devices; and I have found in long experience with this class of apparatus that any form of valve which is adapted when seated to effect a complete seal, and which is arranged to be automatically operated for opening and closing, is comparatively valueless for the purpose of controlling stored up fluid pressure in a system of the character shown in this application; for the reason that in case of any valve which is held forcibly seated for a long time,—as the interval between fires in a given building,—and requiring operation for opening to afford the fire protection, either the

valve or its seat is liable to become deformed by the pressure by which it is forcibly seated, and to become permanently set in such deformed condition, so that on being automatically opened and subsequently automatically closed, the cooperating faces of the valve and seat are not only liable, but extremely likely, to be found unmated when they are reset at closed position; and accordingly leakage almost invariably is found occurring after an instance of automatic opening and closing of such valve.

When a fire protective system of this character is installed in an extended structure of several floors and many apartments, there will be a considerably large number of these pressure release devices, which present a valve held forcibly seated and arranged to be opened by a temperature-responsive device on occurrence of fire danger in the particular apartment; and when in accordance with the most usual practice, all of these pressure release devices are installed in continuing,—or as it might be called, permanent,—connection with a fluid pressure storage tank, which serves the entire building and all the fire protective systems thereof, it will be seen that there is necessity for vigilant attention to the pressure gauge connected to the storage tank and pressure lines therefrom; because a leak in any one of the fluid pressure lines,—at any one of the pressure release control valves,—will cause lowering and eventual exhaustion of the fluid pressure throughout the entire installation, and in all apartments of the entire building. And when such lowering of pressure is indicated to the watchman by the pressure gauge, the point of leakage must be promptly located by inspecting all the pressure release control valves. And when a fire has occurred and been extinguished due to the effective operation in the manner described, of one or more of the pressure release control valves in the system, complete inspection of the entire system throughout the building is necessary to locate the individual pressure release control device or devices which have been operated, and in which the strut-seated valved elements must be removed and re-

placed by perfectly set and tested duplicates, and since these valved devices are in most instances necessarily for their function located at high points in the several apartments,—usually at the ceiling,—the construction is desirably such as to afford ready access to the housings for removal and replacement of the valve elements which have suffered displacement in the operation under 10 fire conditions, without dismounting the housing from the pipe system; and the construction shown and above outlined as hereinafter described in detail, is designed for meeting these requirements.

15 The invention may first be described in general terms without reference to the mechanical details.

It consists of a compressed air tank or reservoir in any convenient form arranged 20 for connection with a source of compressed air or means for charging it by pumping, this reservoir being connected by a discharge conduit with any number and variety of devices and apparatus in different parts of the building to be protected, arranged to be set in operation for their respective functions of protection against fire by the action of compressed air upon some elements or features of the respective devices or apparatus, when 25 the compressed air is admitted from the compressor or reservoir to the discharge conduit by the operation of the temperature-responsive device which is associated with the valve which controls the compressed air discharge 30 for opening said valve by the action of the temperature-responsive device, due to predetermined temperature conditions affecting said responsive device.

40 The means for affording protection from fire may comprise means for causing discharge of water for extinguishing the fire, or means for cutting off particular areas of the apartment from the fire, as by closure of fire doors, or means for defeating air circulation by which the fire may be spread from apartment to apartment. The thermostatic element for operating the valve for discharge 45 of compressed air may be any type of structure having an element whose change of form or dimensions under dangerous temperature in the vicinity can be utilized for causing movement of connections for operating the valve.

55 A preferred form of such thermostatic device is embodied in the construction shown in the drawing and hereinafter described in detail, and is of the type in which the valve-operating movement of the temperature-responsive member of the thermostatic device 60 results from rapid change of temperature, and is not produced by slow change, such as might occur from normal change of atmospheric temperature in the absence of dangerous fire.

Referring to the drawing in detail:

The compressed air reservoir is shown at 20 in the form of a relatively long tube having at one end a fitting, 21, adapted for connection with a source of compressed air or for connection with a pump for charging it directly, such adaptation being indicated by a screwed-in plug, 22, which may be removed for temporarily connecting a pipe leading from the compressed air source or the pump to the inlet passage, 23, which is furnished with a check valve, 24, opening to admit the air under pressure and being seated by reaction of the compressed air for retaining the same while the connection from the pump or compressed air supply pipe is being disconnected and the plug, 22, reinserted.

70 As shown, there is provided a supplemental precautionary plug, 22^x, which is shown screwed into the entrance to the passage, 23, to which for lateral entrance, ports 23^x, are provided, which are cut off by fully screwing in the plug, 22^x, and are partly uncovered by partly screwing back the plug. This supplemental plug may be used as described to ensure the retention of air under pressure against the possibility of the check valve being imperfectly seated by reason of becoming fouled.

75 The reservoir, 20, is arranged at the opposite end for connection with a discharge conduit indicated by a pipe, 26, the connection for discharge from the reservoir to the pipe being controlled by a valve shown at 27 seating at the discharge port, 28, which is formed in a yoke member, 30, arranged to be screwed into the terminal fitting, 39, of the reservoir, said valve being arranged to be held positively seated, preventing discharge by a strut, 29, extending between the valve and an adjusting screw, 31, which is set through the head of the yoke. The yoke and valve, and strut carried by it, are all enclosed in the chamber, 32^a, of a hood member, 32, into which, therefore, the port, 28, opens and which discharges through a centrally apertured plug, 33, screwed into the head of the hood for making connection with the pipe, 26, which is shown connected by a compression coupling, 24, of familiar construction.

80 The hood member, 32, has an aperture laterally opposite the strut, 29, with a flexible diaphragm closing and sealing the aperture; and there is mounted in this diaphragm a stem, 36, which at its inner end rests and is adapted to be thrust against the strut, 29, in the flexure of the diaphragm inwardly with respect to the hood chamber.

85 At its outer end the diaphragm stem is arranged as hereinafter more particularly described, for securement and actuation for such thrust inwardly with respect to the chamber, by a movable element of the thermostat or temperature-responsive device referred to. Such inward thrust it may be un-

derstood operates to displace the strut, which is preferably constructed and arranged for such displacement by breaking, for which purpose it is made of frangible material 5 and may be weakened as shown at 29^a, about midway its length and, as shown, preferably at the point at which the diaphragm stem bears and is thrust against it.

The hood, 32, is arranged to be mounted 10 against the end of the reservoir tube by an air-tight joint, as indicated by packing gasket, 38, interposed at the seating of the hood on the terminal fitting, 39, of the reservoir tube; and the hood is detachably secured to 15 said terminal fitting of the reservoir by screws, 41, set through the base flange, 42, of the hood.

The temperature-responsive element for 20 operating the valve, 27, by displacement of the strut, 29, comprises a larger bar, 50, and a lesser bar, 51, of substantially different cross sectional dimensions mounted side by side in a housing, 52, which extends alongside the tubular reservoir, 20, said housing 25 and tubular reservoir being mounted in fixed relation to each other as hereinafter more particularly described; so that the entire structure comprising the reservoir and the terminal fittings described and the temperature- 30 responsive element comprising the parallel bars and their housing and terminal fittings and operating parts, hereinafter described, may be mounted as a unit in any desired location in the building to be protected.

35 The two bars, 50 and 51, are made fast at one point in the length of each bar, preferably at their ends remote from the discharge end of the compressed air reservoir; and at the other end the lesser bar, 51, extends loosely 40 through a support and guide bearing, as shown at 53, formed by the terminal web, 54, of an elbow terminal member, 55, of the housing, the corresponding end of the larger bar, 50, being made fast to said web and 45 thereby held fixedly at that end with respect to the housing with respect to which the opposite ends of both bars are movable longitudinally with respect to the bars and housing.

50 From this description it may be understood that assuming the two bars made of the same material, or materials having approximately the same thermal conductivity, it will result that upon change of temperature occurring 55 so slowly that the larger bar will become heated through before the substantial elongation of the more slender bar will be caused by that bar being heated through so as to be elongated, and consequently the elongation 60 of the two bars will not be materially different. But in case of a rapid rise of temperature the lesser bar responding promptly to the temperature change by longitudinal expansion, the larger bar being unable to expand longitudinally to any appreciable ex-

tent until the temperature increase has affected it at least half way to a center, it will occur in the earlier part of such temperature rise that the lesser bar will be elongated relatively to the larger bar, and its free end, 54, will be protruded beyond that bearing, while the corresponding end of the larger bar will remain unchanged in position.

Advantage is taken of this action due to rapid rise of temperature, to operate means for displacing the strut, 29, and permitting the hood, 27, to be opened by the air pressure for discharge of compressed air and communication of the pressure through the conduit, 26, for operating the protective devices as indicated above.

For this purpose there is provided in the terminal elbow fitting of the housing, 52, a lever member, 56, pivoted at the lower side 35 of the housing, as shown at 57, said lever being weighted as indicated at 58 and being normally held in upright position by a latch, 60, whose latch nose, 61, engages a latch nose, 62, on the lever, 56.

The latch, 60, pivoted at 64 to the web, 54, above the guide bearing of the bar, 51, has a lug, 63, which carries an adjustable screw, 63^a, with which the protruding end of the lesser bar comes in contact upon predetermined elongation of the bar, 50, and operates the latch, 60, to release the catch, 62, of the lever, 56, permitting the weighted end of the lever to fall, the lever swinging about its pivot. The lever, or the weight which it carries, is provided with a projection, 67, positioned for striking the end of the diaphragm stem in the descent of the weight and the swing of the lever; and the weight is heavy enough so that that encounter serves to thrust the inner end of the diaphragm stem against the strut, 29, and displace it by breaking or otherwise; whereupon the valve, 28, being displaced from its seat,—or if it adheres thereto, being forced open by the air pressure,—the air pressure is admitted to the conduit, 26, for operating the protective device as it will be described.

One type of means for protecting against fire of course consists in fire-extinguishing means, such as a so-called sprinkler system; and in a building equipped with such apparatus the present invention may be installed for cooperating with such sprinkler system by 115 having a branch of the compressed air discharge conduit, 26, extending, as seen at 68, to a device illustrated in detail in Figure 1, and indicated as to its entirety by reference numeral, 70, for opening any number of water discharge heads indicated at 71 of a sprinkler pipe system indicated at 72 for discharge of the water in the apartment in which the fire heat has caused the temperature- 120 responsive device to operate as described for 125 130

connecting the compressed air reservoir with the device, 70.

The device, 70, is a fitting arranged to be interposed between the branch, 68, of the compressed air discharge conduit and a pipe line, 72, having in its extent any number of normally open water discharge heads, 71. This fitting, arranged for connection as seen at 74^a, with the water supply pipe indicated at 74, has between said connection and the connection at 75 with the water discharge head line, 72, a port, 76, controlled by a valve, 77, which is held normally seated by a spring, 78, and which also seats in the direction of the water pressure from the pipe, 74, and is accordingly normally held seated by the water pressure. This fitting has beyond the port, 76, and the connection with the pipe line, 72, a chamber, 79, partitioned by the flexible diaphragm, 80, which is operatively connected with the stem, 81, of the valve, 77, for opening the valve by the flexure of the diaphragm as it may be flexed by the pressure admitted from the port and valve, and which is suitably connected for such operation.

Figure 1 may be understood as showing at 90 a sliding fire door which is normally held at open position by a latch, 91, upon whose release the door will be automatically closed by the means provided for sliding it, as a spring or weight not shown. In this figure the branch, 92, of the compressed air conduit 26 is shown leading to a fitting, 93, which comprises a flexible diaphragm, 94, exposed at one side to the pressure admitting through the pipe branch, 92, and connected for operating the latch, 91, to disengage it from the fire door to release the latter for automatically closing it to cut off the fire from the apartment to which the doorway which it closes leads.

I claim:

1. A construction arranged to be mounted as a unit on the enclosing walls of an apartment to be protected against fire comprising two cooperating members, the first being an elongated chamber arranged for connection at one end with a source of fluid under pressure and having at the other end a valved fitting adapted to be connected for communicating said fluid pressure, and having a valve controlling said communication; a similarly elongated structure comprising elongated temperature-responsive members and a housing in which they are carried arranged to serve as a mounting for said fluid pressure chamber and having said chamber fixedly attached to said housing, the housing having mounted movably on it proximate to the valve fitting of the fluid pressure chamber a part whose movement is controlled by the temperature-responsive action of said temperature-responsive members arranged with respect to said fitting and the valve thereof

for operating said valve for communicating the fluid pressure to fire-protective devices.

2. A construction arranged to be mounted as a unit on a wall of a building to be protected against fire comprising an elongated chamber arranged for connection at one end with a source of fluid pressure and having at the other end a valved fitting adapted to be connected for communicating the fluid pressure to protective devices upon the displacement of the valve from its seat in the fitting, said fitting having valve displacing means exteriorly operable for such displacement, the second member of said unit comprising elongated temperature-responsive elements and a housing in which they are mounted, means associated with said temperature responsive elements and with the valve-displacing means for being brought into operation by the temperature-responsive elements and for operating said valve-displacing means to displace the valve upon the response of said temperature-responsive elements to predetermined temperature conditions in the protected area, said housing being arranged to serve as a mounting for the first member of the unit and having said first unit member fixedly attached to said housing.

3. A valved device adapted to be interposed in a fluid pressure conduit, said valved device consisting of a chamber having an outlet port and an inlet port and a valve seating at the inlet port interiorly of the chamber, means holding the valve normally seated against the inflow to the chamber, and exteriorly operated means for displacing the valve-holding means to release the valve, the valve and the displaceable part of said holding means being wholly within the chamber and unattached thereto or to the displacing means, the valve holding means comprising a displaceable strut, the valve seat having a yoke overhanging the seat and furnished with an adjustable stop for one end of the strut, the chamber having a normally closed opening, and a removable closure, said opening being positioned for affording access from the exterior to said adjustable stop.

4. A valved device adapted to be interposed in a fluid pressure conduit, said valved device consisting of a chamber having an outlet port and an inlet port and a valve seating at the inlet port interiorly of the chamber, means holding the valve normally seated against the inflow to the chamber, and exteriorly seated against the inflow to the chamber, and exteriorly operated means for displacing the valve-holding means to release the valve, the valve and the displaceable part of said holding means being wholly within the chamber and unattached thereto or to the displacing means, the valve holding means comprising a displaceable strut, the valve seat having a yoke member overhanging the seat and furnished with an adjustable stop for one end of

the strut, the outlet from the chamber being aligned with said adjustable stop, whereby upon disconnecting the discharge fitting access is obtained through the outlet port to said adjustable stop for adjusting the same to enforce the secure seating of the valve.

5. A valved device adapted to be interposed in a fluid pressure conduit, said valved device consisting of a chamber having an outlet 10 port and an inlet port and a valve seating at the inlet port interiorly of the chamber, means holding the valve normally seated against the inflow to the chamber, and exteriorly operated means for displacing the 15 valve-holding means to release the valve, the valve and the displaceable part of said holding means being wholly within the chamber and unattached thereto or to the displacing means, the valve holding means being frangible and arranged for displacement to release the valve by breaking, the valve seat 20 having a yoke member overhanging the seat and furnished with an adjustable stop for one end of the valve-holding means, the chamber 25 having a normally closed opening with a removable closure, said opening being positioned for affording access from the exterior to said adjustable stop.

6. An apparatus comprising a fitting arranged for detachably attaching thereto a charging pipe with a plug closing said connection, said fitting having a chamber which is closed at the outer end by a sleeve mounted in the fitting constituting a flow passage 25 from said chamber of the fitting into a fluid pressure chamber, and a check valve in said flow passage opening for flow into the pressure chamber and seating against backflow.

7. The construction defined in claim 6, the 40 check valve seat being formed by an axially apertured bushing drive-fitted in the sleeve,

and the valve having a stem extending through the bushing and furnished with a spider for guidance in the sleeve, and a spring reacting between the spider and the bushing for seating the valve.

8. A fire protective apparatus, adapted to be mounted as a unit on a wall of the building to be protected, comprising two structural elements, the first being a chambered element arranged at one end for connection with a source of fluid pressure and carrying at the other end a valved terminal fitting arranged for connection with fire protective devices, the second being a temperature responsive device comprising temperature-responsive parts and a releasably upheld weighted member, and upholding means operably related to the temperature responsive part for operation thereby upon movement of the temperature-responsive part due to temperature change, for releasing the weighted member, the terminal fitting of the first element being a valve, and displaceable means holding it normally seated, and exteriorly operable means for displacing said holding means exposed for actuation in the path of gravity movement of the releasable weight.

9. The construction defined in claim 8, the valve holding means being a displaceable strut, and the displacing means comprising in combination with a thrust pin, a flexible carrying member carried by the fitting opposite the strut for holding the thrust pin normally against the strut, said flexible carrying means being positioned for impact of the falling weight thereagainst.

In testimony whereof, I have hereunto set my hand at Chicago, Illinois, this 1st day of November, 1930.

EMIL TYDEN.
